UNITED STATES PATENT OFFICE.

HENRY W. LYON, OF BRIDGEPORT, CONNECTICUT.

DESIGN FOR A GARMENT-SUPPORTER.

SPECIFICATION forming part of Design No. 24,872, dated November 12, 1895.

Application filed September 28, 1895. Serial No. 564,042. Term of patent 7 years.

To all whom it may concern:

Be it known that I, HENRY W. LYON, a citizen of the United States, residing at Bridgeport, in the county of Fairfield and State of Connecticut, have invented and produced a new and original Design for Garment-Supports; and I do hereby declare the following to be a full, clear, and exact description of the invention, such as will enable others skilled in the art to which it appertains to make and use the same.

The accompanying drawing is a side elevation of a flat sheet-metal garment-support, showing my design.

The leading feature of my design is the scroll-like opening extending through from the obverse to the reverse sides of the flat body of the garment-support, said scroll being of a general **S** shape and being formed by a large circular opening at the top and a smaller circular opening at the bottom, these openings being connected by a deflected gate,

so that angular portions are formed at the upper and lower ends of said gate, which angular portions project inwardly from opposite sides of the gate at the points where said gate respectively joins the circular openings.

1 is the large circular opening at the top; 2, the smaller circular opening at the bottom; 3, the deflected gate which connects these openings, and 4 the angular portions at the upper and lower ends of said gate and projecting from opposite sides of the gate at the points where the latter joins said openings.

I claim—

The design for garment supports, substantially as shown in the accompanying drawing.

In testimony whereof I affix my signature in presence of two witnesses.

HENRY W. LYON.
